Patented Mar. 25, 1924.

UNITED STATES PATENT OFFICE.

ERNEST L. STULTZ, OF KANSAS CITY, MISSOURI, ASSIGNOR TO WESTERN CABINET & FIXTURE MFG. CO., OF KANSAS CITY, MISSOURI, A CORPORATION OF MISSOURI.

REFRIGERATOR.

Application filed June 5, 1922. Serial No. 566,040.

To all whom it may concern:

Be it known that I, ERNEST L. STULTZ, a citizen of the United States, residing at Kansas City, in the county of Jackson and State of Missouri, have invented certain new and useful Improvements in Refrigerators; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to refrigerators and particularly to a refrigerator so designed that advantage can be taken of the low temperature of the water resulting from the melting of the ice to reduce the temperature 20 within the food receiving shelves of the refrigerator.

25 In carrying out my invention I prefer to combine the ice with salt so that the melting ice forms a brine at a relative low temperature. This brine is trapped within the refrigerator and being cool, obviously cools the surrounding atmosphere.

It has generally been proposed to pass off 30 the drippings from the ice as quickly as possible and in this respect my invention differs from the general practice as I trap the drippings or brine by providing an overflow for the waste pipe which will maintain the brine at a predetermined level on the cooling conduit.

35 I prefer to arrange ice chambers at opposite ends of the refrigerator and flow the brine from the opposite ends toward the center so that the brine will pass adjacent to the shelves which contain the food, preferably along the outer edge so as to maintain the air, particularly adjacent to the shelves, cool.

40 There are certain novel details of construction embodied along with the generic idea of the invention and these are described in detail in the following description.

In the drawings,

45 Fig. 1 is a perspective view of a refrigerator constructed in accordance with my invention, parts being broken away to show the interior construction thereof.

Fig. 2 is a detail perspective view of the overflow drain, and

Fig. 3 is a vertical, longitudinal, frag-

mentary, sectional view through the refrigerator.

The casing or box 1 of the refrigerator is shown as relatively long. The walls may consist of any suitable heat insulating material. At each end of the refrigerator are shown two drawers which constitute the ice containing receptacles. The drawers 2 and 3 at one end are substantially like the drawers 4 and 5 at the other end. Each drawer consists of a metallic receptacle 6, having guide rails 7 and 8 on its respective sides which are received in guides 9 and 10, suitably supported within the refrigerator box 1.

Since each drawer is substantially a counterpart of the other drawers, it is not necessary to describe each one in detail. The bottom of each drawer is provided with openings 11, through which the drippings 75 from the ice may pass. For the upper drawers 2 and 4 there is a catch basin or pan 12, one for each drawer, and these pans 12 contain overflow pipes 13 which extend above the bottom thereof and discharge through the bottom into a longitudinal conduit 14, running along the edge of the shelf 15 of the refrigerator between the two ends.

Each drawer 2 and 4 is provided with a false bottom 16, to contain the ice, the false bottom being of less area than the drawers so that the water may flow over it and preferably through it, to be discharged through the openings 11 in the bottom of the drawers 2 and 4 so that it may be received in the 80 catch basin or pan 12. This catch basin has an overflow outlet 13, secured in an opening in the bottom of pan 12 and extending above said bottom so as to maintain a body of liquid in said pan. 95

I prefer to salt the ice, that is, mix the ice with coarse salt so that it will melt at a lower temperature than ordinary ice to provide a cold brine water to pass through the conduit 14. At the center of the conduit 14 100 is an overflow pipe 17, extending from the bottom of the conduit a suitable distance and discharging into the waste sump 18 at the bottom of the refrigerator, the sump being connected to a suitable waste or sewer. 105

The overflow pipe 17 is provided with two vertical slots 19 and 20, which extend from the floor of the conduit 14. These are normally closed by a valve 21, rotatable within the overflow pipe 17 and having a portion 110

22 by means of which it may be turned. The valve is provided with diametrically opposite slots 23, only one being shown, and these slots are adapted to register with the slots 19 and 20 when the valve is in one position to drain off the brine. When the slots 23 are turned out of register with the slots 19 and 20, the slots 19 and 20 will be valved off so that the brine must reach the top of
10 the flow-off pipe 17 to flow over its edge before it can escape into the sump 18. The top of the overflow pipe 17 does not extend beyond the top 24 of the conduit 14 so even though the valve is in closed position, the
15 brine will not rise above the plate or top 24.

The conduit 14 receives the brine from the pans 12 at the rate at which the ice melts so there is always cooling water being fed into the conduit 14, replacing the brine which is
20 being warmed by absorbed heat within the refrigerator case.

The lower drawers 3 and 5 are formed similar to the drawers 2 and 4 and they discharge into the bottom of the case along an inclined floor portion 25, which may empty
25 into the sump 18. The sump has a collar 26 which is an overflow collar, as clearly seen in Fig. 3, the collar being of sufficient height to permit a predetermined level of the brine in
30 the conduit 14', formed by the floor 25 and the cover plate 27.

The refrigerator may have an inclined wall 28 at the front with a plurality of doors 29, the number being whatever is required for easy access to the shelf 15 and there may be a corresponding number of doors 30 so that access may be had to the
35 lower shelf 31.

It will be apparent that the salted ice may
40 be readily placed in the drawers and the

drawers closed so that if the doors 29 and 30 are closed, the ice box will be sealed. The melting ice will form a brine passing through the conduits 14 and 14' to cool the central space of the refrigerator, in which
45 are located the shelves 15 and 31. There will always be some brine adjacent to the shelves because the overflow pipes will maintain a predetermined level in both conduits.

The refrigerator is very simple in construction, easily accessible and well adapted to perform the service for which it is intended.

While I have illustrated the device as provided with ice chambers at the respective ends of the casing, it is obvious that for small units a single ice chamber may be employed at one end of the casing, the conduit communicating therewith in the same manner as if two ice chambers were used.

What I claim and desire to secure by Letters Patent is:

In a refrigerator, a casing comprising an ice chamber and a shelf for the support of articles to be cooled, an ice drawer slidably suspended in said chamber, having an apertured bottom, a false bottom in said drawer having edges spaced from the walls of the drawer to permit drainage from the false bottom to the apertured bottom, a catch pan
60 in said chamber below the ice drawer, a conduit leading from beneath the catch pan along said shelf, an overflow pipe having an intake in said pan above the bottom thereof and delivering into said conduit, and an
65 overflow waste pipe having an intake in said conduit above the bottom thereof.

In testimony whereof I affix my signature:

ERNEST L. STULTZ.
